MOUNTING

Norman E. Haslop, North Ridgeville, Ohio, assignor to The Lakeside Metal Stamping Co., Cleveland, Ohio

Application May 23, 1950, Serial No. 163,749

3 Claims. (Cl. 20—57.5)

1

This invention relates to a mounting for overhanging structures such as canopies, awnings, and the like.

At the present time there are many types of roof-like structures, canopies, awnings, and louvered structures adapted to be fastened to a vertical wall such as a side of a house or building. In hanging or mounting of these structures on the wall the mounting must be strong enough to withstand weather conditions. The mounting should also be water tight whereby water running down the side of the wall will run off the overhanging structure and not between the overhanging structure and the wall.

An object of my invention is to provide an economical and sturdy mounting for canopies and similar structures.

Another object is to provide a canopy mounting wherein the back side edge portion of the canopy top serves as a flashing.

Another object is to provide a mounting comprising a substantially U-shaped channel member fastenable to the wall and a depending tie member fastenable along the back side edge of the canopy top and seatable in the channel member.

Another object of the invention is to provide a mounting for a roof-like structure wherein the top of the structure has a back edge resiliently urged against the wall to serve as a flashing and prevent rain water running down the wall through the mounting.

Other objects and a fuller understanding of the invention may be had by referring to the following description and claims, taken in conjunction with the accompanying drawings, in which:

Figure 1 is a front elevational view of a canopy supported by my mounting.

Figure 2 is an end view of a canopy supported by my mounting.

Figure 3 is a fragmentary enlargement of the mounting used for mounting the canopy of Figures 1 and 2 to a vertical wall.

The mounting herein described and disclosed may be used on roof-like structures, canopies, louvered structures, awnings or any other similar structure which are to be mounted on a vertical wall such as a wall of a house or other building. In the present instance the drawings and description as well as some of the claims refer to the mounting of a canopy since I have mounted canopies in this disclosed manner.

The canopy illustrated in Figures 1 and 2 as a canopy top member 10 and end panels 11 which are fastened to opposite ends of the canopy top member 10. The reference character 12 design-

ates the vertical wall on which the canopy is mounted.

The mounting for the canopy is best illustrated in the fragmentary enlarged view of Figure 3. This mounting comprises a modified U-shaped channel opening upwardly and bearing reference character 15. The modified U-shaped channel 15 has openings 16 in one side thereof through which screws 17 or other suitable fasteners extend to secure the U-shaped channel to the wall 12. The modified U-shaped channel 15 has a length substantially equal to the distance between the end panels 11 or the length of the top member 10.

15 Fastened to the undersurface of the top member 10 is a tie member 18 which extends downwardly and is seatable in the elongated modified U-shaped channel which opens upwardly. In the present instance the tie member 18 is in the form of an angle member having one side bolted to the undersurface of the top member 10 by bolts 19. The other leg 20 of the angle member or tie member depends from and extends downwardly into seating engagement with the modified U-shaped channel 15. The tie member 18 is fastened along the back side and to the undersurface of the top member 10.

I have found it desirable to provide the top member 10 with an upwardly extending flashing portion 21 extending along the back side thereof. 30 The flashing portion is joined with the major portion of the top member 10 and is resiliently cooperative therewith whereby the top edge 22 of the flashing portion is urged against the wall 12. The flashing portion 21 is preferably provided with screw holes 23 through which holding screws 24 may be screwed into the wall 12 to hold the tie member 18 seated in the modified U-shaped channel 15.

It has also been found desirable to provide the top member 10 with crimped portions 25 extending parallel to the flashing portion 21. These crimped portions 25 add stiffness, strength, and better water shed characteristics to the canopy or other structure. Water must run substantially horizontally along these crimped portions and off the ends of the top member 10. The crimped portions 25 are preferably constructed with the same dimensions and at the same angle to the major part of the top member 10 as the flashing portion.

In mounting a canopy on a wall the modified U-shaped channel 15 is secured to the wall in a horizontal plane with the channel opening upwardly. The tie member 18 has previously been fastened to the undersurface of the top member

along the back side thereof. The canopy is next positioned above the channel and the depending tie member 18 aligned for seating in the modified U-shaped channel. After the weight of the canopy rests on the tie member which is seated in the U-shaped channel the holding screws may be inserted through the flashing portion 21 to prevent unseating of the tie member from the channel.

It is understood that other modifications of the present invention may be resorted to without departing from the spirit and scope thereof and that the present disclosure has been made only by way of example with the invention being claimed as follows.

What is claimed is:

1. In a canopy mounted on a vertical wall, a canopy including a roof portion extending outwardly from the vertical wall at a first angle thereto and also including an upturned back edge portion joining the roof portion in a resilient bend line portion and at a second angle thereto, said second angle being greater than said first angle before said canopy is mounted on said wall, a canopy supporting means horizontally secured to said wall, said canopy and said supporting means having cooperative pivot connections located generally at said bend line, and means between said roof portion and said wall to hold said roof portion at said first angle to said wall and to decrease said second angle when said canopy is mounted on said wall by resiliently bending said bend line portion for causing said back edge to seat tightly against said wall thereby constituting a waterproof flashing.

2. In a canopy mounted on a vertical wall, a canopy including a roof portion extending outwardly from the vertical wall at a first angle thereto and also including an upturned back edge portion joining the roof portion in a resilient bend line portion and at a second angle thereto, said second angle being greater than said first angle before said canopy is mounted on said

wall, a modified U-shaped channel member horizontally secured to said wall and opening upwardly, a depending member on said canopy extending generally along said bend line and pivotally seated in said channel member, and means between said roof portion and said wall to hold said roof portion at said first angle to said wall and to decrease said second angle when said canopy is mounted on said wall by resiliently bending said bend line portion for causing said back edge to seat tightly against said wall thereby constituting a waterproof flashing.

3. In a canopy mounted on a vertical wall, a canopy of springable sheet material including a roof portion extending outwardly from the vertical wall at a first angle thereto and also including an upturned back edge portion joining the roof portion in a bend line and at a second angle thereto, said second angle being greater than said first angle before said canopy is mounted on said wall, a modified U-shaped channel member horizontally secured to said wall and opening upwardly, a depending member on said canopy extending generally along said bend line and pivotally seated in said channel member, and means between said roof portion and said wall to hold said roof portion at said first angle to said wall and to decrease said second angle when said canopy is mounted on said wall by resiliently bending said bend line portion for causing said back edge to seat tightly against said wall thereby constituting a waterproof flashing.
